UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

STEAM OR SIMILAR ENGINE.

SPECIFICATION forming part of Letters Patent No. 741,388, dated October 13, 1903.

Application filed April 13, 1898. Serial No. 677,449. (No model.)

To all whom it may concern:

Be it known that I, ELIHU THOMSON, a citizen of the United States, residing at Swampscott, in the county of Essex and State of 5 Massachusetts, have invented certain new and useful Improvements in Steam or Similar Engines, of which the following is a specification.

The chief object of my invention has been 10 to improve the construction and operation of engines to be used with steam, superheated or not, compressed air, or other gases, so as to obtain from an engine of simple construction economical results in the use of steam, &c., 15 which will be comparable with the results ordinarily obtained from complex engines, such as ordinary compound or compound condensing engines. I have found in the practice of my invention that engines of as small a capacity as from one to three horse-power may 20 when constructed and operated according to my invention yield results in the economy of steam which, so far as I am aware, have been entirely unknown hitherto and which approach or equal the economies obtained by 25 complex types of engines of the compound or triple compound class of much larger capacity and which far exceed the economical results of the complex forms of engines of 30 the same capacity, and I am thus enabled to do away with complex valve mechanisms, transfer-passages for steam, multiple cylinders of varying diameter, &c.

The principle upon which my improved 35 engine is founded is substantially as follows: I provide a large clearance-space back of the piston which by the instant opening of the valve when the crank is on the dead-point and the piston down is filled almost instantaneously with steam up to boiler-pressure. This steam or compressed gas is expanded 40 rapidly during the motion of the piston forward and the supply cut off very soon after the crank passes the dead-point. In this manner there is an almost instantaneous filling of the clearance-space with steam, which is almost immediately shut off before the piston has moved through any great angle, so 45 that the work of the engine depends almost altogether upon the expansion of the steam admitted to the clearance-space. As the pis-

ton moves forward and the steam expands the power is given to the crank almost entirely by expansion of the charge admitted, and lastly the steam is discharged through 55 a proper exhaust-port, which may be of any desired construction, but which as I have shown it is of the simplest possible character—viz., a set of openings uncovered by the piston at its extreme outward stroke. The 60 steam left in the cylinder as the piston returns is compressed into the clearance-space, giving an amount of compression depending upon the ratio between the volume of the clearance-space and the clearance-space plus 65 the space traversed by the piston. This compression-pressure will generally be a fraction of the boiler-pressure. Thus it may be fifty pounds above atmosphere while the boiler-pressure is one hundred and fifty or more. 70 My construction insures the separation of temperatures, inasmuch as at no time does the steam reverse its progress or direction of movement in the cylinder between admission and exhaust. The admission end of the 75 cylinder therefore can remain at the temperature of the steam of admission, while the exhaust portion of the cylinder is at a low temperature—that of the steam cooled by expansion in the abstraction of work in moving 80 the piston. In the same way there is no possibility of condensed water or the cooled products after expansion being thrown back upon the hot end or admission end except 85 what is demanded for compression, in itself a heating process. The cylinder at the end of each power-stroke is cleared of cooled and condensed products, such as condensed water. The exhaust-ports being situated as far as possible from the inlet-ports they do not 90 share each other's temperature. It is to these and other features of construction to be pointed out to which I attribute the high economies of steam which I have obtained for small-powered and simple engines. 95

I am enabled by simple means to obtain a compound effect, and so further increase to a certain degree the economy.

My invention relates chiefly, therefore, to engines of simple character whereby the effects of expansion and compounding are obtained without the necessity for the com-

plexity of compound engines. The usual expedients of non-conducting lagging or steam-jacketing may be resorted to to protect the cylinders from external cooling. I find, however, that any plain non-conducting lagging is generally sufficient.

Figures 1 and 2 are plan and elevation, respectively, of a compound engine embodying the features of my invention. Figs. 3, 4, 5, 6, and 7 are diagrammatic views of the parts of the engine shown in Figs. 1 and 2. Fig. 8 is a modification in the manner of operating the admission-valve.

Referring first to Figs. 1 and 2, two pistons (which may be of different sizes) P and P² are provided with suitable cranks set relatively to each other, so that piston P leads piston P² in revolution by, say, ninety degrees up to one hundred and twenty degrees, as may be selected. Admission to cylinder C, which may be called the "high-pressure" cylinder, is made into a large clearance-space or untraversed space at the back when piston P is down. The valve V is shut soon after the crank to piston P passes the dead-center. The steam in expanding pushes piston P forward and uncovers port E, which admits equalization of pressures between the two cylinders C and C² back of their pistons. This occurs, preferably, at a point some fifty degrees or sixty degrees of revolution of the crank of piston P before reaching the outer dead-center. The steam from C then follows piston P² outwardly, while piston P returns, covers exhaust-port E, and compresses what steam remains in cylinder C after such covering of E preparatory to receipt of new steam through valve V into the clearance-space. In cylinder C² there need be but little clearance-space. The steam taken over from cylinder C goes on expanding in C² until piston P² is fully out.

It will be seen that no exhaust-valve is provided for the low-pressure cylinder, the exhaust being controlled by the motions of the pistons themselves. This greatly simplifies the construction and leaves only a single valve V to be operated for a compound engine. The construction is as follows: The communicating ports E for transferring the steam from cylinder C to cylinder C² are arranged so as to be uncovered not only at the extreme outward stroke of piston P, but also for a similar period on the extreme inner stroke of said piston, the said piston P being made short enough to permit this. There are also provided exhaust-openings E², which are uncovered by piston P² at its extreme outer position, as shown in Fig. 1. The operation will be better understood by reference to Figs. 3, 4, 5, 6, and 7, which are simply diagrammatic views of the parts in the engine of Figs. 1 and 2 at different times of revolution. In Fig. 3 the admission steam-valve V is open and the clearance-space back of piston P is filling with steam, while the crank corresponding thereto is just at dead-

center or a little beyond. Meanwhile since the crank moved by piston P² follows crank of piston P at right angles, or thereabout, piston P² is at its most rapid rate of motion inward and is discharging steam through port E, which has been uncovered by piston P in its backward stroke. Valve V closes and piston P moves forward, as in Fig. 4, but before reaching the center communicates with cylinder C² through port E just as piston P² begins its forward motion, as indicated. Both pistons are moving forward in this case with the port E open between them and steam passing from cylinder C to cylinder C². This is continued, as in Fig. 5, while the crank of piston P is passing over its outward dead-center, piston P² making its effective forward stroke meanwhile. Finally port E, which remained open, is closed by the backward motion of piston P, as in Fig. 5, and piston P² is ready to open exhaust-port E², and so drop the pressure back of piston P² to atmosphere or below when condensers are employed.

Fig. 6 shows piston P nearly completing its backward stroke and opening port E to the atmosphere or condenser from cylinder-space in C², while piston P² has started back ready to expel what remains in cylinder C² through port E to atmosphere or condenser. This expulsion goes on through stage Fig. 3 while valve V is open and is completed in the stage (shown in Fig. 7) intermediate between that of Fig. 3 and Fig. 4, where piston P has begun its outward stroke and piston P² is just about completing its inward stroke. Piston P is shown as just having covered the port E in its outward stroke in Fig. 7, while piston P² now on further motion compresses what slight amount of steam remains into its own clearance-space, which is preferably made only slight, as above stated. I am thus enabled to secure the effects of compounding in a simple type of construction of engine.

Where the initial movements of the piston in my engine are given by extraneous power, as by turning over the crank at the start, I may dispense with mechanism for operating the valve V even and cause the piston itself to work the valve, it being only necessary that the valve V shall open for a short interval while piston P is nearly at rest on the inner dead-point. In Fig. 8, C is the cylinder, as before, P the piston, and V is a valve the stem of which projects inward toward the piston, so as to be struck by the piston and opened for a short interval as the piston is almost down or while the crank is passing the dead-center. This admits steam to the clearance-space S while said crank is on dead-center and for a very short interval before and after that point is reached. The opening of valve V thus becomes automatic, and the steam is exhausted at port E, as before. This arrangement is useful where the engine is to run at a determined speed once having been started, as in driving dynamos for electric lighting. To lessen the blow of

the piston in opening valve V in running at good speed, the ends of piston P may be bored out into a small cylindrical cavity and a disk or piston inserted therein which engages with the valve-stem. A small amount of fluid in the space so provided between the small piston or valve-operating piston and the large piston proper acts to damp the blow struck on the valve-stem. A spring Q may also be provided, holding back the small piston p to a definite position when not engaged with the valve-stem.

In describing the engine of my invention no means of governing the speed have been described or shown, it being understood that various means of governing may be employed where it is necessary that the engine shall be given a regular speed. Thus centrifugal throttle-governors may be used to throttle the steam, or the engine may be governed on the hit-and-miss principle, as with gas-engines—that is, the valve which admits steam may be caused by the governor to intermit in its opening when it tends to be accelerated beyond normal speed—and this intermission may be put under the control of centrifugal or other governors similar to those used in gas-engines.

With simple engines of as low as three to five horse-power constructed substantially as in Figs. 1 and 2, giving a compression of about fifty pounds and with a boiler-pressure of two hundred pounds dry steam, a brake horse-power can be expected to be obtained with an expenditure of about twenty pounds per horse-power hour, the speed of the engine being between six hundred and seven hundred revolutions per minute. Considerably better results can be obtained with larger engines, while my invention secures

also a relatively high light-load efficiency as compared with complex forms of compound engines.

What I claim as new, and desire to secure by Letters Patent of the United States, is—

1. In a compound engine, the combination of a high-pressure cylinder; a low-pressure cylinder; ports in the high-pressure cylinder which admit steam to the low-pressure cylinder when uncovered by the forward movement of the piston, and exhaust the low-pressure cylinder when uncovered by the backward movement of the piston, additional exhaust-ports for the low-pressure cylinder which are uncovered by the forward movement of the low-pressure piston, and a valve controlling the admission of steam to the high-pressure cylinder.

2. In a compound engine, the combination of a high-pressure cylinder, a low-pressure cylinder, a plurality of exhaust-ports formed in the high-pressure cylinder which are uncovered at each end of the stroke of the high-pressure piston but are unaffected by the movements of the low-pressure piston, a plurality of exhaust-ports which are formed in the low-pressure cylinder and are covered and uncovered by the movements of the low-pressure piston, an outwardly-opening puppet-valve admitting steam to the cylinder, means driven by the engine for opening the valve, and an automatic device for closing the valve.

In witness whereof I have hereunto set my hand this 11th day of April, 1898.

ELIHU THOMSON.
